UNITED STATES PATENT OFFICE

130,946

DESIGN FOR A GAME BOARD

**Jackson T. Isbell, Centralia, Mo., assignor to
A. B. Chance Company, Centralia, Mo., a cor-
poration of Missouri**

Application October 10, 1941, Serial No. 103,713

Term of patent 14 years

To all whom it may concern:

Be it known that I, Jackson T. Isbell, a citizen of the United States, residing at Centralia, in the county of Boone and State of Missouri, have invented a new, original, and ornamental Design for a Game Board, of which the following is a specification, reference being had to the accompanying drawing, forming part thereof.

The figure is a plan view of a game board, showing my design. The article is of no appreciable or substantial thickness.

I claim:

The ornamental design for a game board, as shown and described.

JACKSON T. ISBELL.
